UNITED STATES PATENT OFFICE

121,613

DESIGN FOR A SPRAY GUARD FOR MACHINE TOOLS

Milburn A. Hollengreen and Ralph E. Price,
Waynesboro, Pa., assignors to Landis Tool
Company, Waynesboro, Pa.

Application March 29, 1940, Serial No. 91,346

Term of patent 14 years

To all whom it may concern:

Be it known that we, Milburn A. Hollengreen and Ralph E. Price, citizens of the United States of America, residing at Waynesboro, in the county of Franklin and State of Pennsylvania, have invented a new, original, and ornamental Design for a Spray Guard for Machine Tools, of which the following is a specification, reference being had to the accompanying drawing, forming part thereof.

Figure 1 is a front perspective view of a spray guard for machine tools showing our new design; and

Figure 2 is a rear perspective view thereof.

We claim:

The ornamental design for a spray guard for machine tools, substantially as shown.

MILBURN A. HOLLENGREEN.
RALPH E. PRICE.
